CONNECTOR WITH CONVERSATION TIMING

Ernest H. Gatzert, Rochester, N. Y., assignor to General Dynamics Corporation, Rochester, N. Y., a corporation of Delaware

Application July 9, 1956, Serial No. 596,692

4 Claims. (Cl. 179—18)

My invention is concerned with telephone systems in general and more particularly with connector or final selector circuits suitable for use in so-called step-by-step type telephone systems.

In the past, connector circuits have been made which are capable of determining whether or not a selected line circuit termination is in busy condition. Such connectors have been supplied with features providing for (1) selecting signals for transmission to selected line circuits and subscriber lines, and (2) timing connections established through the communication channel of the selector. In order to provide these features, it has been the practice to provide separate connecting or actuating relays individual to the connector apparatus associated with each feature. This practice increases the number of relays individual to each connector and is objectionable because the cost of each connector is increased correspondingly.

Accordingly, it is an object of my invention to provide a new and improved connector and circuit.

Another object of my invention is to provide a new and improved connector circuit in which the number of relays is minimized.

Another object of my invention is to provide a new and improved connector in which one relay is used for three different functions such as conducting busy test, ringing control, and timing control functions.

I accomplish these and other objects in a telephone system having a connector circuit and switch. The switch has a set of wipers and a plurality of terminal sets disposed for engagement by the wiper set. Apparatus such as a line circuit and subscriber lines is individually connected to each of the terminal sets. Means is provided for independently changing each of the terminal sets from its normal, idle condition to a busy condition when the corresponding line and line circuit is in use. The connector also includes means for directly advancing the wiper set into engagement with any one of the terminal sets in order to make other means, including the wiper set of the connector, ultimately effective for extending a communication channel through the selector to a selected terminal set.

According to the invention, the connector circuit also includes a special multi-purpose relay having a winding and a plurality of contacts. Following the engagement of one of the terminal sets by the wiper set, first connecting means is operative for making the special relay effective to determine the busy or idle condition of the selected set of terminals. In the event that the relay indicates that the selected terminal set is in busy condition, certain contacts on the relay are effective for indicating the busy condition of the selected terminal set by rendering the communication channel extending means inoperative, thereby preventing the extension of such a connection to a busy selected terminal set.

In order to transmit distinctive signals to the apparatus terminated on a selected terminal set, a source of sig-

2

naling current is provided. Within the connector, signaling means including certain other contacts on the special relay are effective for connecting the current source to the selected one of the terminal sets. Other means associated with the signal source are thereafter effective in response to the operation of the channel extending means for controlling the operation of the special relay in order to carry out the distinctive signaling operation.

The connector circuit also includes means operative in response to the transmission to the selector of an off-hook supervisory signal from the line connected to the selected terminal set effective in the well-known manner for rendering the signaling means ineffective and for completing the communication channel. Another source is effective for transmitting timed signals to the connector. Means operative in response to the operation of the supervisory signal responsive means are thereafter operative under the control of those timing signals for causing the aforesaid special relay to be reoperated a predetermined time interval after the receipt of the off-hook supervisory signal. Still other contacts on the special relay are thereupon effective for blocking the communication channel in order to prevent the transmission of speech signals over the communication channel.

For a better understanding of my invention as set forth in the following description and the appended claims, reference is made to the attached drawings, in which:

Fig. 1 shows, in block form, a typical telephone system including a connector which incorporates the preferred embodiment of my invention;

Fig. 2 shows, in block form, equipment for originating a call through the telephone system of Fig. 1; and, in schematic form, a part of the connector incorporating the preferred embodiment of my invention; and

Figs. 3 and 4 show, in schematic form, the remainder of the connector incorporating the preferred embodiment of my invention. Fig. 4 additionally includes, in block form, apparatus to which the connector has access.

Power for operating the system is drawn from several sources. The first of these is a battery, the most positive plate or terminal of which is connected to ground and is hereafter referred to in the written description as "ground" and in the drawings as (+). The other, ungrounded terminal or plate of the battery is referred to in the written description as "battery" and in the drawings as (-). A second source of power is the well-understood alternating current ringing generator connected in series with a battery. Again, the most positive plate of the battery is connected to ground and is hereafter referred to as "ground" in the written description, and as (+) in the drawings. The ungrounded side of the battery-generator combination is referred to as "ringing generator" in both the drawings and written description.

Extending a connection to the connector

In order to extend a call from a calling subscriber station, such as 21, well-known hookswitch means at the station is effective upon the removal of the telephone from its hookswitch for causing apparatus (not shown) to extend a connection from the telephone station through apparatus individual to the calling station, such as line circuit LC21, to a selector, such as 22. Thereafter, the transmission of a directive signal to selector 22 is effective for advancing the selector wipers, shown collectively as W22, to the terminal set on which conductors, shown collectively as 23, are terminated. Conductors 23 interconnect the terminal set of selector 22 to a connector shown in Figs. 2-4, so that upon the described advance of wipers W22 a communication channel is extended from calling station 21 to the connector. The completion of the channel is also effective for seiz-

ing the connector and preparing it to receive directive signals or trains of digit impulses from the calling station dial. Thus the seizing circuit is effective in the well-understood manner for operating calling bridge relay 210 from ground through the upper winding of relay 210, break contacts 202, incoming tip conductor T, the corresponding tip conductors of the preceding selector, line circuit and calling line, the station dial contacts, the ring conductor of the calling line, line circuit, and preceding selector, incoming ring conductor R, break contacts 203, and the lower winding of relay 210 to battery. Relay 210 thereupon operates.

The operation of relay 210 is effective for completing an operating circuit for release delay relay 220 from ground through break contacts Z21 of the release magnet ZM21, make contacts 211, and the winding of release delay relay 220 to battery. Operation of relay 220 connects ground to the incoming conductor S at make contacts 221 in order to mark the final selector busy and thereby to guard the connector against seizure by other exchange equipment subsequently attempting to extend calls through the final selector. The operation of relay 220 also completes an operating circuit for the primary delay relay 300 from ground through make contacts 224, primary off-normal break contacts P22, and the upper winding of relay 300 to battery. The operation of relay 220 also completes an operating circuit for secondary delay relay 420 from ground through make contacts 224, secondary off-normal break contacts S41, and the upper winding of relay 420 to battery. Relays 300 and 420 thereupon operate.

Directive operation of the connector

In order to directively operate the connector, the subscriber at calling station 21 operates the station dial in order to send directive signals or trains of digit impulses over the operating circuit of relay 221 to the connector. Each digit impulse in such a train momentarily opens the operating circuit of relay 210 so that relay 210 is released and reoperated in response to each impulse in each train of impulses. In the description that follows, the first digit is assumed to comprise five such impulses, and the second digit six. During the transmission of a train of impulses, relay 220, being a slow release type, remains operated during the time that relay 210 is released, even though the above-traced operating circuit for relay 220 is opened momentarily at make contacts 211.

Primary direction advance.—During the transmission of the first digit, the primary magnet PM31 is energized in response to each release of relay 210 in order to move the wiper set including wipers T1, R1, S1 and HS1 away from normal position in the primary direction. The number of steps taken is the same as the number of impulses in the first transmitted train of digit impulses. The advance of the wiper set away from its normal position is effective for operating primary off-normal means in order to open the above-traced operating circuit for relay 300 at break contacts P22. During the primary direction advance of the wiper set, relay 300, a slow release type, is held steadily in its operated condition by the intermittent energization of the lower winding of relay 300 in the manner next described. Upon each release of relay 210, a circuit for activating magnet PM31 and the lower winding of relay 300 is completed from ground through break contacts Z21, break contacts 212, operated contacts 226, 425 and 303, and magnet PM31 to battery; the same ground source is extended through the lower winding of relay 300 to battery. When the transmission of the first digit has been completed, relay 210 comes to rest in its operated condition. Thus, the above-traced holding circuit for relay 300 and the energizing circuit for magnet PM31 are opened at break contacts 212. Relay 300 restores at this time in order to prepare the selector to receive the second digit. At this time, the wiper set has been advanced five steps in the primary direction away

from its normal position and is at rest opposite the fifth level of terminal sets to which the switch has access.

Secondary direction advance.—Upon the transmission of the second digit, the wiper set is advanced in its secondary direction within the selected (fifth) level in order to engage the one of the plurality of terminal sets within the selected level corresponding to the number of impulses in the second digit. Thus, each release of relay 210 during the transmission of the second train of impulses is effective in response to the operation of relay 420 and the release of relay 300 for causing one of a series of energizations of the secondary advancing means including secondary magnet SM31. Each energization of magnet SM31 is effective to advance the wiper set one additional step within the selected level.

During the time that magnet SM31 is being energized, the lower winding of relay 420, a slow release type, also can intermittently be energized so that relay 420 can be made to remain steadily operated even though its upper winding is deenergized. Thus, when the above-traced energizing circuit for the upper winding of relay 420 is opened at break contacts S41 by the operation of the secondary off-normal means (caused by the advance of the wiper set in its secondary direction), relay 420 is maintained operated until after the second digit impulse train has been transmitted to the selector. The circuit for energizing magnet SM31 and the lower winding of relay 420 is traced from ground through break contacts Z21, break contacts 212, make contacts 226 and 425, break contacts 304, and magnet SM31 to battery; the same ground source is extended through an obvious circuit to the lower winding of relay 420 and battery. When the second digit impulses have been transmitted, relay 210 comes to rest in its operated condition. Thus, the above-traced circuit for energizing the lower winding of relay 420 and magnet SM31 is opened at break contacts 212. Relay 420 thereupon releases.

Busy test.—At the conclusion of the transmission of the first and second digits to the connector, it is seen that the wiper set comprising wipers T1, R1, S1 and HS1 has been advanced into engagement with a particular set of terminals. Each terminal set to which the wiper set has access is normally in an idle condition and ready to be seized by switching equipment such as the final selector now being described. Seizure of apparatus such as line equipment 42 individually connected to each terminal set by other means within the system results in the application of a busy indicating ground potential over a conductor, such as S2, to the one of the terminals in the selected set which is engaged by wiper S1.

Upon the advance of the wiper set into engagement with any one of the terminal sets, means comprising relay 310 within the final selector is effective for conducting a test in order to determine whether or not the selected terminal set is in busy condition. Thus, during the time interval between the transmission of the last impulse of the second train of digit impulses to the connector has been completed and the release of the slow release type relay 420, contact means on relay 420 is effective for extending a connection from the one of the terminal sets to which busy indicating potential may be connected and the winding of the relay 310. Assuming for the moment that the selected terminal set is in busy condition, ground potential present on conductor S2 and wiper S1 is extended through make contacts 423, break contacts 419, and the winding of relay 310 to battery. The subsequent release of relay 420 (described above) opens the above-traced operating circuit at make contacts 423. Thus, it is seen that if relay 310 is to operate at this time, it must be during the interval that relay 420 is in its operated condition.

The operation of relay 310 and the release of relay 420 is effective for closing a holding circuit for relay 310 from ground through make contacts 225 and 317, break contacts 424 and 419, and the winding of relay 310 to battery. The operation of relay 310 is effective in re-

sponse to the released condition of switching relay 410 (the function of which is to be more fully explained in the following paragraphs) for completing a circuit to connect busy indicating tone to the calling telephone station 21. The latter circuit is traced from the grounded busy tone source (not shown) through break contacts 421, make contacts 312, break contacts 412a, the upper winding of answer bridge relay 200, break contacts 411a, blocking capacitor C21, break contacts 202, conductor T, the above-traced connection to calling station 21, conductor R, break contacts 203, and the lower winding of relay 210 to battery. The operation of relay 310 is also effective for opening the operating circuit of switching relay 410 at break contacts 316 for reasons that are to be explained presently.

In the event that busy indicating ground potential is absent from the terminal connected to conductor S2, relay 310 fails to operate. Upon the release of secondary delay relay 420 following the completion of transmission of the second digit to the final selector and in response to the released condition of relay 310 the connector is prepared for switchthrough operation where the communication channel between the connector and the called station is partially completed. This so-called switchthrough operation is next described.

Switchthrough operation.—In response to the release of relay 420 and the unoperated condition of relay 310, a circuit for operating switching relay 410 is completed as follows: from battery through a resistance within line circuit 42, conductor S2, wiper S1, break contacts 422, the lower winding of relay 410, break contacts 316 and make contacts 225 to ground. The energization of the lower winding of relay 410 is effective for causing the operation of preliminary make contacts 417 which thereupon completes a circuit for fully operating relay 410. The latter circuit is traced from ground through make contacts 224, make contacts 417 and the upper winding of relay 410 to battery. The operation of relay 410 is effective for extending a communication channel from the final selector signaling apparatus to the called line station 43 in the manner to be described. The operation of relay 410 is also effective for placing direct ground on wiper S1 and a corresponding terminal of the engaged terminal set at make contacts 416 in order to mark the equipment connected to the selected terminal set as busy to other equipment within the exchange.

Returning to the consideration of relay 310, it is seen that the operation of relay 310 in response to the busy condition of the called line terminal set is effective for opening the above-traced energizing circuit for the lower winding of relay 410 at break contacts 316. This has the effect of preventing the operation of switching relay 410 and avoids the possibility of extending the communication channel through the final selector to a busy terminal set. Similarly, the operation of relay 410 is effective for opening the above-traced operating circuit for relay 310 at break contacts 419 in order to prevent the operation of relay 310 over the above-traced busy test circuit after the switchthrough operation has taken place.

Signaling the called line.

A ringing generator common to a plurality of connectors such as the one being described here is provided for furnishing low frequency alternating current signals in the well-known manner to the signaling device such as a ringer at the called telephone station. Following the operation of switching relay 410, a circuit is prepared for completing a connection between the ringing generator and one of the conductors such as R2 connected to the terminal of the set engaged by the wiper set. During the time that relay 310 is operated (in the manner to be explained) the circuit is traced from ringing generator through make contact 315, the upper winding of relay 400, break contacts 404a, make contacts 414, and wiper R1 to conductor R2. During the time that relay 310 is released, the above-traced circuit from the upper winding

of relay 400 to conductor R2 is connected to battery through break contacts 314 on relay 310. Thus, it is seen that the reoperation of relay 310 is effective in response to the operation of relay 410 for completing the above-traced circuit including the ringing generator.

The ringing generator operates in combination with an electrically separate interrupter circuit. The interrupter is used for cyclically producing a plurality of direct current code signals of the duration and/or sequence required to signal any one of the parties on the subscriber lines included in the system. These signals are brought to the connector banks over a plurality of conductors. One code is transmitted over each conductor. In order to signal a particular party on a particular line, such as station telephone 43 on line 45, the appropriate signal conductor is connected to one of the terminals of the selected set which is also individual to station 43. The code signal is thereupon transmitted to the winding of relay 310 within the connector in order to operate relay 310 during the time that the appropriate signal is being transmitted over the line connected to the selected terminal set. Such a connection may be traced from signal lead 44 to conductor HS2, wiper HS1, break contacts 408, make contacts 418, and the winding of relay 310 to battery.

After the ringer of the called station 43 has been operated and the station telephone is removed from its hookswitch, the well-known ring trip circuit comprising a low impedance path between conductors T2 and R2 is completed at the station. The completion of the low impedance path is effective for closing an operating circuit for ring trip relay 400 which is traced from ground through break contacts 401a, make contacts 411b, wiper T1, conductor T2, the low impedance path between conductors T2 and R2, conductor R2, wiper R1, make contacts 414, break contacts 404a and the upper winding of relay 400. In the event that relay 310 is in its unoperated condition at this time, the circuit is completed to battery through break contacts 314. In the event that relay 310 is in operated condition at this time, the circuit for operating relay 400 is completed through the direct current part of the ringing generator by way of make contacts 315.

The completion of the above-traced circuit for relay 400 is effective for energizing that relay to the point where preliminary make contacts 407 are closed. The closing of contacts 407 completes an operating circuit for relay 300 over the following circuit: from ground through make contacts 224 and 407, break contacts 405 and the upper winding of relay 300 to battery. Relay 300 thereupon operates. The operation of relay 300 is effective for closing an operating circuit for the lower winding of relay 400 from ground through make contacts 224, S42, and 302 and the lower winding of relay 400 to battery. Relay 400 thereupon operates to close a locking circuit for itself from ground through make contacts 224, 407, and 406 and the lower winding of relay 400 to battery. The operation of relay 400 is effective for opening the above-traced circuit for reoperating relay 300 at break contacts 405. Relay 300 thereupon releases.

The operation of relay 400 is effective for disconnecting wiper HS1 from its above-traced connection to the winding of relay 310. Relay 310 thereupon stops following code signals transmitted over conductor HS2. The operation of relay 400 is effective for completing an operating circuit for answer bridge relay 200. The circuit is traced from ground through make contacts 412b, the upper winding of relay 200, make contacts 401b and 411b, wiper T1, conductor T2, the loop of the station 43, conductor R2, wiper R1, make contacts 414, 404b, 413, and 402b and the lower winding of relay 200 to battery. Relay 200 thereupon operates in order to reverse the direction of current flow through conductors T and R to calling station 21 at reversing contacts 201, 202, 203, and 204.

The operation of relay 400 is also effective for completing a communication channel through the final selector from the incoming conductors T and R to wipers T1 and R1, respectively, and thereby is effective to interconnect the calling station 21 to the called station 43. In the case of the tip side of the communication channel, the circuit is traced from incoming conductor T through make contacts 201, blocking capacitor C22, break contacts 313, make contacts 404b and 414 and wiper R1. The ring side of the channel is traced from incoming conductor R through make contacts 204, blocking capacitor C21, break contacts 311, make contacts 401b and 411b and wiper T1. Conversation then takes place and may continue between calling station 21 and called station 43 until the parties hang up or until conversation through the connector is forcibly ended. The forced ending or conversation timing operation is next described.

Conversation timing

In addition to the process of reversing the direction of current flow over the loop of the calling telephone station, the operation of relay 200 is effective for starting the conversation timing cycle by connecting the common timing lead TP1 to the winding of timing A relay 320. The circuit is traced from conductor TP1 through make contacts 206, break contacts 325 and 336 and the winding of relay 320 to battery. Another interrupter common to a plurality of connectors of the type being described is effective for placing direct current signals in a particular sequence on conductors TP1, TP2, H1, H3, and CWT. The sequence in which these signals appear is described in the following paragraphs. Upon the appearance of the first ground signal connected to conductor TP1 occurring after relay 200 operates, relay 320 operates over the above-traced circuit and closes a locking circuit for itself from ground through make contacts Z21 and 326, break contacts 336 and the winding of relay 320 to battery.

The operation of relay 320 is effective for connecting conductor TP2 to the winding of timing relay 330. The circuit is traced from conductor TP2 through make contacts 324, break contacts 335 and the winding of relay 330 to battery. Upon the next appearance of a momentary ground signal on conductor TP2, relay 330 is operated and establishes a locking circuit for itself from ground through make contacts 205 and 334 and the winding of relay 330 to battery.

The operation of relay 330 is effective for transferring relay 320 from its above-traced locking circuit including make contacts 326 to a connection to first holding conductor H1. The latter circuit is traced from conductor H1 through make contacts 327 and 337 and the winding of relay 320 to battery. Thereafter, relay 320 is held in its operated condition from a ground signal present on conductor H1 at the time relay 330 operates. Upon the completion of a cycle of operation of the other interrupter, the ground signal is momentarily removed from conductor H1 so that relay 320 releases. The release of relay 320 and the operation of relay 330 is effective for connecting common timing conductor H3 and the winding of relay 310. The circuit is traced from conductor H3 through make contacts 332, break contacts 319 and 321, make contacts 331, 409 and 418, and the winding of relay 310 to battery. Upon the appearance of the next ground signal on conductor H2, relay 310 re-operates.

The reoperation of relay 310 is effective in response to the operation of relays 400 and 331 for establishing for itself a locking circuit from ground through make contacts 224 and 318, break contacts 321, make contacts 331, 409, and 418 and the winding of relay 310 to battery. At this time, reoperated relay 310 is further effective for opening the above-traced communication channel through the connector at break contacts 311 and 313, thereby blocking the talking channel established from

calling station 21 to called station 43 at the end of a predetermined time interval measured from the time relay 200 operates. It is to be noted that the operation of relay 410 is effective at this time for preventing the application of busy tone to the calling station 21 by opening the above-traced circuit for applying busy tone at break contacts 412a. Similarly, the operation of ring trip relay 400 is effective for making those contacts on relay 310 including contacts 314 and 315 which were effective for applying signaling current to the called station 43 ineffective by opening the previously traced circuit for applying signaling generator to the called station at break contacts 404a.

15

Release by the subscribers

At any time during the course of the extension of a connection from the calling to the called station, the calling station 21 controls the release of the connector. Thus, when the telephone at calling station 21 is returned to its hookswitch, relay 210 is released for a time interval sufficient to allow relay 220 to release. The release of relay 220 is effective for removing ground from the previously traced holding circuit of relays 400 and 410 at make contacts 224. Relays 400 and 410 thereupon release. The release of relay 410 is effective for closing an energizing circuit for release magnet ZM21. The circuit is traced from ground through break contacts 415 and 222, parallel off-normal make contacts P21 and S21, and the winding of magnet ZM21 to battery. The energization of magnet ZM21 restores the wiper set from its advanced primary and secondary positions to normal position.

The release of relay 220 is also effective for removing ground from the previously traced locking circuit of relays 310, 320, and 330 at make contacts 221 and 225 so that the latter are similarly restored in the event that they had been operated at the time relay 220 releases. The release of relay 220 is further effective for removing ground from incoming sleeve conductor S at contacts 221 in order to remove the busy condition from the connector and thereby make the connector available for the extension of other calls.

While I have shown and described a particular embodiment of my invention, it will be obvious to those skilled in the art that changes and modifications may be made without departing from the spirit of my invention in its broader sense. I therefore aim in the appended claims to cover all such changes and modifications as fall within the true spirit and scope of my invention.

What I claim is:

1. In a telephone system, a connector including a switch, said switch having a wiper set and a plurality of terminal sets for engagement by said wiper set, means connected to each of said terminal sets for independently changing each terminal set from its normal idle condition to busy condition, means for directly advancing said wiper set into engagement with any one of said terminal sets in order to select one of said terminal sets, a multi-purpose relay having a plurality of contacts, means operative following the engagement of one of said terminal sets by said wiper set for controlling said relay to indicate the busy or idle condition of the selected one of said terminal sets, means for preparing a communication connection through said selector by way of said wiper set to any one of said terminal sets, means including certain of said contacts for rendering said connection preparing means inoperative in the event said relay indicates the selected one of said terminal sets is in busy condition, a source of signaling current, means including certain other of said contacts for connecting said source to the selected one of said terminal sets in order to transmit distinctive signals to the selected one of said terminal sets, means for transmitting supervisory signals to any one of said terminal sets, means operative in response

to the receipt of a supervisory signal subsequently transmitted to the selected one of said terminal sets and to said selector for rendering said signaling current connecting means ineffective and for completing said communication connection through said wiper set to the selected one of said terminal sets, means for transmitting timing signals to said connector, means operative in response to the operation of said supervisory signal responsive means for causing said relay to be controlled by said timing signal source, and means including still other contacts on said relay for preventing the transmission of communicating signals through the communication connection of said connector.

2. The telephone system set forth in claim 1 wherein said means for causing said relay to be controlled by said timing source is operative in response to the operation of said connection preparing means in order to prevent said relay from operating from timing signals during the period when signaling current is being transmitted to the selected one of said terminal sets.

3. In a telephone system, a connector including a switch, said switch having a wiper set and a plurality of terminal sets for engagement by said wiper set, each of said terminal sets including a particular terminal, means connected to each of said terminal sets operative for connecting a busy indicating potential to said particular terminal of the corresponding set in order to change the set from its normal idle condition to busy condition, means for directly advancing said wiper set into engagement with any one of said terminal sets in order to select one of said terminal sets, a multi-purpose relay having a winding and a plurality of contacts, means operative upon the engagement of any one of said terminal sets by said wiper set for connecting said particular terminal of the selected set to said relay winding, said relay thereupon being operative in response to the application of busy potential to its winding for indicating a busy condition on the selected one of said terminal sets, means for preparing a communication connection through said connector by way of said wiper set to the selected one of said terminal sets, means including certain of said contacts operative in response to the operation of said relay for rendering said connection preparing means inoperative in order to prevent the extension of a connection through said connector to a busy one of said terminal sets, a source of signaling current, means comprising certain other of said contacts operative in response to the operation of said relay for connecting said source to the selected one of said terminal sets, a source of control signals, said connection preparing means being also operative for connecting said control signals to the winding of said relay in order to cause distinctive signals to be transmitted to the selected one of said terminal sets, means for transmitting a supervisory signal to any one of said terminal sets, means operative in response to the transmission of a supervisory signal to said connector through said wiper set and the selected one of said terminal sets for disconnecting said certain other contacts in said signaling current source from the selected one of said terminal sets, for disconnecting said control signal source from the winding of said relay, and for completing the communication connection through said selector, means for transmitting timing signals to said connector, means operative in response to the operation of said supervisory signal responsive means for connecting said timing signal source to said relay winding in order to operate said relay a predetermined time interval following the receipt of a

supervisory signal, and still other of said contacts effective in response to the operation of said relay and said connection preparing means for opening said communication connection in order to prevent the transmission of signals through said communication connection a predetermined time interval following the receipt of a supervisory signal.

4. In a telephone system, a connector including a switch, said switch having a wiper set and a plurality of terminal sets for engagement by said wiper set, each of said terminal sets including a particular terminal, means connected to each of said terminal sets operative for connecting a busy indicating potential to said particular terminal of the corresponding set in order to change the set from its normal idle condition to busy condition, means for directly advancing said wiper set into engagement with any one of said terminal sets in order to select one of said terminal sets, a multi-purpose relay having a winding and a plurality of contacts, a relay momentarily operative upon the engagement of one of said terminal sets by said wiper set for connecting said particular terminal of the selected one of said sets to said relay winding, said multi-purpose relay being operative in response to the application of a busy indicating potential to its winding and nonoperative in the absence of a busy indicating potential to said winding, means for thereafter maintaining said multi-purpose relay in operated condition, a communication connection through said connector by way of said wiper set to the selected one of said terminal sets, a switchthrough relay operative for partially completing said communication channel, means including certain of said contacts operative in response to the operation of said multi-purpose relay for rendering said switchthrough relay inoperative in order to prevent the extension of a connection from said connector to a busy one of said terminal sets, a source of signaling current, means including certain other of said contacts operative in response to the operation of said multi-purpose relay for connecting said signaling current source of the selected one of said terminal sets, a source of control signals, said switchthrough relay being operative for connecting said control signal source to said multi-purpose relay winding in order to transmit distinctive signals to the selected one of said terminal sets, means for transmitting supervisory signals to the selected one of said terminal sets, said signaling current selecting means including a ring trip relay operative in response to a supervisory signal subsequently transmitted from the selected one of said terminal sets to said connector for disconnecting itself and said signaling current source from the selected one of said terminal sets, for disconnecting said control signal source from said multi-purpose relay winding, and for completing said communication connection, means operative in response to the operation of said switchthrough and said ring trip relays for connecting said timing signal source to said multi-purpose relay winding, and still other of said relay contacts operative in response to the operation of said multi-purpose relay and said switchthrough relay for opening said communication connection in order to prevent the transmission of signals through said communication connection a predetermined time interval following the receipt of a supervisory signal.
